165,513

FRONT PLATE FOR A TYPEWRITING
MACHINE

Theodore G. Clement, Rochester, N. Y., assignor
to L. C. Smith & Corona Typewriters, Inc.,
Syracuse, N. Y., a corporation of New York

Application July 21, 1951, Serial No. 15,983

Term of patent 14 years

(Cl. D64—11)

To all whom it may concern:

Be it known that I, Theodore G. Clement, a citizen of the United States of America and resident of Rochester, in the county of Monroe and State of New York, have invented a new, original, and ornamental Design for a Front Plate for a Typewriting Machine, of which the following is a specification, reference being had to the accompanying drawing, forming a part thereof.

In the drawing:

Figure 1 is a front elevation of a front plate for a typewriting machine, showing my new design;

Figure 2 is a rear elevational view thereof;

Figure 3 is a side view thereof; and

Figure 4 is a sectional view on the line 4—4 of Figure 1.

The essential features of my design for a front plate for a typewriting machine reside in the parts shown in full lines. The front plate is

made of translucent material, so that the ridges on the back will show through from the front as shadow lines, as seen most clearly in Figure 1.

I claim:

The ornamental design for a front plate for a typewriting machine, substantially as shown and described.

THEODORE G. CLEMENT.
